UNITED STATES PATENT OFFICE.

LEWIS BUSH, JR., OF CHICAGO, ILLINOIS, ASSIGNOR TO THE AMERICAN MACHINERY COMPANY, OF SAME PLACE.

MACHINE FOR GRINDING CUTTER-KNIVES.

SPECIFICATION forming part of Letters Patent No. 297,565, dated April 29, 1884.

Application filed June 1, 1883. (No model.)

To all whom it may concern:

Be it known that I, LEWIS BUSH, Jr., of Chicago, in the county of Cook and State of Illinois, have invented certain new and useful 5 Improvements in Machines for Grinding Cutter-Knives; and I do hereby declare that the following is a full, clear, and exact description thereof, reference being had to the accompanying drawings, and to the letters of reference 10 marked thereon, which form a part of this specification.

This invention relates to an improvement in sharpening-machines, for use in factories or other places where wood-working machinery 15 is employed, for grinding the cutter-knives of planing or similar machines. It relates more particularly to machines for the purpose above stated, having a rotary grinding-disk mounted upon an arbor having stationary bearings, and 20 means for supporting and moving the cutter-knives to be ground with reference to the grinding-disk. Its object is to provide an improved construction in the class of grinding-machines above referred to, and also to provide a combined machine for the purpose above 25 mentioned and for sharpening saws.

As it relates to devices for supporting and feeding the cutter-knives in a grinding-machine of the character described, my invention 30 consists in an improved means for giving a vibratory motion to the cutting-edge of the knife during its contact with the rotary grinding-disk; in improvements in the devices for adjusting the knives in relation to the said grinding-disk, and in improvements in the devices 35 for moving the said knives longitudinally with reference thereto, as will be hereinafter fully set forth.

As an improved construction in combined 40 machines for the purposes above mentioned, my invention consists in the combination, with a single rotating arbor carrying two grinding-disks of emery or other substance, of mechanism for supporting and moving cutter-knives 45 with reference to one grinding-disk upon said arbor, and devices for supporting and moving a circular or other saw with reference to the other grinding-disk, so as to produce the desired form in the saw-teeth, and to accomplish the necessary feed-movement in the saw. 50

The devices for moving and feeding a saw

above mentioned, and which are shown in the drawings, have been made the subject-matter of a separate application, filed simultaneously with this, and form no part of the present invention. 55

In the accompanying drawings, Figure 1 is a perspective view of a combined saw-sharpener and cutter-knife grinder embodying my invention. Fig. 2 is a vertical, central, longitudinal section of the same, taken upon the line x x of Fig. 3. Fig. 3 is a partial transverse section, taken upon the line x x of Fig. 2, and showing the knife-grinding devices alone. Fig. 4 is a fragmentary plan view of the top 65 of the machine, showing the end of the knife-carrying slide and the devices thereon for supporting and adjusting the knife.

As illustrated in the drawings, the main frame of the machine consists of two end castings, A, a front plate, A', and a rear girt, A². Upon the top of the said frame is mounted an arbor, B, having bearings in boxes b, supported by standards b', and provided with two grinding-disks, B' and B², the latter disk being used 75 in connection with other devices shown for sharpening saws, and the former in connection with the knife-grinding mechanism, as hereinafter described.

C is the main driving-shaft, which is located in the lower part of the machine longitudinally thereof, and has bearings in boxes c, supported upon the lower cross-pieces of the end castings, A. The said driving-shaft is provided with a pulley, C', from which motion is transmitted to the arbor B by means of a belt, C², which passes over said pulley and a pulley, B³, upon the said arbor. An idler, B⁴, is placed between the standards b', upon a shaft, b⁴, at a point opposite the top edge of 80 the frame-plate A', over which idler the belt C passes, such idler being necessary on account of the relative positions of the arbor and the driving-shaft, in order to prevent contact of the belt with the frame. The driving-shaft C is also provided with a worm, c', which meshes with a worm-wheel, D', upon a transverse shaft, D, by which shaft the devices for giving the requisite movements of the saw-sharpening devices are operated. 85 The said shaft D is mounted in bearings d, secured to the inner face of the end casting, A, 90 95 100

and a clutch, D^2 , is arranged to connect the worm-wheel D' with said shaft, so that it may be disconnected from the driving-shaft C when desired.

5 The devices shown for reciprocating the saw so as to bring its teeth periodically in contact with the grinding-disk B^2 , and the feeding devices for rotating it during such reciprocatory movement will be briefly described, 10 and are as follows: The saw to be sharpened is secured to an arm, E' , adjustably attached to a vertically-sliding plate, E , placed upon the frame of the machine beneath the disk B^2 . The said plate E receives a reciprocatory 15 movement by means of a lever, G , which is centrally pivoted at g to the machine-frame, and is connected at one of its ends to the said plate E , and at its opposite end to a crank-pin, d , upon the end of the shaft D . The plate E 20 is constructed to slide in a guide-plate, F , which is adjustably attached to the frame-plate A' , so as to permit the direction of the reciprocation of the plate E and the saw carried thereby to be changed with reference to 25 the grinding-disk. Means for adjusting the position of the saw upon the arm E' and said arm upon the plate E , for adjusting the fulcrum of the lever G , and the length of the connection between the end of the said lever and the crank-pin d , are also provided for the purposes and in 30 the manner fully set forth in the application for Letters Patent above referred to.

For the purpose of giving the necessary rotary feed motion to the saw, so as to bring the 35 teeth thereon one by one to the grinding-disk, as the said saw is reciprocated, a vertical lever, H , is pivoted to the machine-frame, and provided upon its upper end with a feed-finger, h , the said feed-finger being pivoted 40 loosely upon said lever, so that its free end will fall into the depressions between the teeth and force said teeth forward when the said lever is oscillated. The lever H is operated by a horizontal lever, I , which receives its motion 45 from an eccentric, d' , upon the shaft D , through the medium of a lever, I' , and pitman I'' . A form-block, H' , is secured to the lever H , against the edge of which the end of the lever I bears, and the said block is kept in contact 50 with the said lever by means of a spring, H^2 .

Other details of construction in the devices shown for supporting and moving a saw are more fully described in the application before referred to, and their operation is fully set 55 forth therein, and need not be further explained in connection with the present application, as such devices, as before stated, form in themselves no part of the present invention.

60 B' is the disk for grinding cutter-knives, which, as shown, is placed upon the end of the arbor B opposite to the disk B^2 . The cutter-knives to be ground are supported upon a sliding bed, K , which is placed in guides l , formed 65 in a bed-piece, L , which is supported at its ends upon the top of the end castings, A , of the machine. The sliding bed K preferably

extends the entire length of the machine, and is provided with means for supporting the cutter-knives to be ground, consisting of two 70 arms, M , which are pivoted to the said bed-plate, one near each end thereof, and are rigidly connected at their ends by a longitudinal plate, M' , to which the cutter-knives are attached. The plate M' is supported in such 75 position with reference to the grinding-disk B' that a cutter-knife thereon will be presented at a desired angle to the periphery of said disk, and is adjustable both as to its distance from said disk and its angle thereto, as will 80 be hereinafter described. The bed-plate K is moved or reciprocated longitudinally, for the purpose of causing a knife or cutter secured to the plate M' to be operated upon by the grinding-disk over the entire length of its cutting-edge. Such movement is preferably given to the bed-plate by means of a worm, N , attached to a rotating shaft, N' , which worm engages a rack, K' , upon the bed-plate K , an automatic reversing-gear being used to change 85 the direction of motion of said shaft at the limits of the movement of the bed-plate in each direction. The worm-wheel shaft N' is mounted in bearings n , placed upon brackets secured to the side of the bed-plate L , and motion is 90 given thereto from a shaft, O , by means of spur-wheels N^2 and O^2 , Fig. 2, upon said shafts, respectively, and an intermediate idler, P , mounted upon a shaft, P' . The shaft O is provided with two fixed pulleys, O^2 , which are 95 placed a short distance apart thereon, and a loose pulley, O^3 , mounted upon the said shaft between the said fixed pulleys.

Upon the driving-shaft C , opposite the pulleys mentioned, is placed a broad-faced pulley, C^3 , and motion is transmitted from the said driving-shaft to the shaft O by means of two belts, Q and Q' , placed around the pulley C^3 and the pulleys O^2 and O^3 . The belt Q' is crossed or twisted, and an automatic shifting device is provided for moving said belts Q and Q' alternately from the fast to the loose pulleys upon the shaft U , so as to periodically reverse the motion of the said shaft.

The shifting device mentioned consists of a 115 lever, R , Figs. 2 and 3, pivoted upon a stud, r , fixed upon the bed L , said lever having two arms, R' and R^2 , provided with loops r' and r^2 upon their lower ends, which engage the belts Q and Q' , respectively. The said lever R is operated by two stops, S , one of said stops being placed upon the sliding bed K , near each end thereof. The said stops are placed so as to strike the upper end of the lever R when the said bed reaches the limit of its movement 120 in each direction, and the belts Q and Q' are thereby shifted, first one and then the other belt being caused to run upon the loose pulley O^3 , so as to periodically reverse the direction of rotation of the shaft O and the direction of motion of the bed K in a well-known manner. The stops S are attached to the bed-plate K , so as to be adjustable longitudinally thereon, and by changing the position of said 125 130

stops the reversal of the movement of said bed-plate in either direction may take place at any point desired, according to the length of the cutter-knife to be sharpened and the 5 position in which it is secured upon the bed-plate. For the purpose of allowing the adjustment of the stops S upon the bed-plate K, said stops are secured thereto by means of bolts s, which pass through slots k in said bed- 10 plate, as shown.

In order to prevent the article being ground in the machine described from receiving a concave shape upon the beveled face formed by the grinding-disk, (said shape depending upon 15 the radius of the said grinding-disk,) I have provided means for giving said article a lateral vibratory movement while its edge is in contact with said disk. Such vibratory motion may be in a straight line, and in the plane 20 of the beveled face of the article being ground, so as to cause said face to be perfectly flat; but in the machine shown, and as preferably constructed, such vibratory motion is given to the plate M', and the article is moved in an arc 25 of the center of which is the pivotal point of the arms M. As the radius of said arc is relatively large in proportion to the amplitude of the vibration given to the article being ground, and as said radius is constant, the result obtained 30 is practically the same as though the vibratory movement took place in a straight line.

As a means of producing the vibratory motion described in the plate M', said plate is supported upon a vibrating table, T, by means of 35 projections m, which rest upon the surface thereof. The table T is arranged longitudinally at the front of the bed L, and extends the full length thereof, so as to afford a bearing 40 for the projections m during the longitudinal reciprocation of the plate M', and is made of the requisite width to allow the necessary lateral movement of the said projections when they are moved by the lateral adjustment of 45 the plate M' upon the sliding bed K. The said table is pivoted at its inner edge to the bed L, and supported at its outer edge by a pitman, U, which connects it with a lever, V, said lever being pivoted at one end to the 50 bracket b', and provided at the other with a slot, v, which engages a crank-pin, n', upon the end of the shaft N', by which means the said lever is oscillated upon its pivot, and the table T thereby given a vibratory motion. 55 The table T extends the entire length of the bed L, as before stated, and is pivoted thereto at each end by means of bolts t, passing through lugs t', cast upon the under face of the said table, and lugs l' upon the said bed L. The 60 pitman U is pivoted to a lug, t'', upon the central portion of the said table, and its lower end is pivotally attached to an eye, u', formed upon the upper end of a bolt, U', which bolt passes through a slot, v', in the lever V, and secured 65 therein by a nut, u'', upon its lower end. The bolt U' may be moved in the said slot, and

clamped in its changed position by means of said nut u', and the pivotal point of the lower end of the pitman U thereby adjusted longitudinally of the lever V, as desired. By changing the distance of the bolt U' from the pivotal point of the lever V, the amount of movement given to the table T may be varied, as desired. The lever V, as shown, is, for convenience, pivoted upon the projecting end of the shaft 70 b', upon which the idler B' is mounted; but said lever may be pivoted otherwise, if desired.

In order to allow a lateral adjustment of the cutter-supporting plate M' with reference to the grinding-disk, the arms M are pivoted to sliding blocks M², which blocks are centrally apertured for the insertion of screw-shafts K², said shafts being supported in lugs k² upon the bed-plate K and transversely thereto. The said screw-shafts are provided 80 with milled heads K³, by which they may be rotated, and the blocks M² thereby moved as desired in adjusting the position of the plate M'. 85

For the purpose of permitting an adjustment of the position of the article supported 90 upon the plate M' with reference to the angle at which said article is presented to the grinding-disk, the said plate M' is connected to the arms M by means of a hinged joint, so as to allow a rotary movement of said plate upon 95 said arms. The said hinged joint is formed between plates M³, attached to the ends of the plate M' and the arms M by means of pivot-bolts m², which pass through the overlapping portions of said plates M³ and the said arms. The 100 plates M³ are preferably cast integral with the plate M', and are provided, as shown in Fig. 3, with arms M⁴, extending beyond their pivotal points, the ends of which arms M⁴ are held in position with reference to the arms M 105 by means of adjusting-screws M⁵, by which the plates M³ may be turned upon their pivotal connections with the arms M, and the angle of the plate M' to said arms thereby varied as desired. The adjusting-screws M⁵ are preferably inserted in threaded apertures in lugs m³, cast upon the arms M, as shown, the ends of 110 said arms M⁴ being moved vertically when the screws are turned in said lugs by means of collars m⁴ upon the said screws, which collars are 115 placed above and below the ends of said arms. The pivot m², by which the plate M' is joined to the arms M, is, as shown, placed between the projection m, by which the plate M' is supported upon the table T and the pivotal point 120 of the arm M. By this construction the plate M' and the edge of the knife thereon are held at substantially the same height above the table T, and consequently in the same position with reference to the grinding-disk at whatever 125 angle the plate M' is placed, for the reason that when the said plate M' is turned upon the pivot m², the outer ends of the arms M will rise or fall, as the case may be, and the said plate will turn around the point of contact between the projection m and the table T as a 130 stationary center.

The cutter-knives, which are to be sharpened, may be secured to the face of the plate M' in any desired or preferred manner. The knife shown in the drawings is provided with a series of transverse slots, and is held upon the said plate by bolts m⁵, having enlarged heads, which enter a longitudinal T-groove, m⁶, formed in the face of said plate. The position of the back edge of the knife is determined, and the said knife may be moved in adjusting it in position by means of set-screws M⁷, which pass through lugs m⁸ upon the upper edge of the plate M', and bear at their ends against the rear edge of said knife.

15 For the purpose of supporting the table T immovably, when desired, the pitman U may be disconnected from the bolt U' and secured upon the side of the standard b' by means of a tap-bolt, which is passed through a slot, u⁹, 20 in said pitman, and inserted in an aperture, b¹⁰, in the face of said standard, as shown in dotted lines in Fig. 3.

The surface of the plate M', against which the knife to be ground rests, or a portion of 25 said plate near the cutting-edge of said knife, is preferably provided with shallow transverse grooves m¹¹, as shown in Figs. 3 and 4. These grooves are for the purpose of allowing the access of air to the lower surface of the knife, 30 so as to prevent, to a greater or less extent, heating the knife by the action of the grinding-disk thereon.

It is found in grinding-machines that it is necessary to cause the peripheries of grinding-disks to travel at a definite speed, in order to attain the most favorable results, so that in the use of two disks upon one arbor they must be of approximately the same diameter, in order that both may work effectively at the 40 same time. It would therefore be necessary in combining a saw-sharpening device in the manner stated with the knife-grinding machine using a large grinding-disk, as heretofore, to make the grinding-disk of the saw-sharpening device correspondingly large. 45 Such construction would be both inconvenient and expensive, and is avoided in the combined machine described by giving the vibratory motion before described to the cutter-knives to be sharpened, and thereby making possible the use of small grinding-disks both for the knife-grinding and saw-sharpening devices, which disks are placed upon the same arbor and used at the same time.

55 I claim as my invention—

1. The combination, with a rotary grinding-disk and a longitudinally and laterally movable plate constructed to support a knife in position to be ground, of a movable table constructed to support said plate, and means constructed to give a vibratory motion to said table, substantially as described.

2. The combination, with a rotary grinding-disk, of a longitudinally-movable bed-plate, 65 K, a knife-supporting plate, M', pivotally attached to said bed-plate and laterally adjustable thereon, a pivoted table, T, constructed

to support said plate M', and means for vibrating said table, substantially as described.

3. The combination, with a rotary grinding-disk and with a rotating shaft, N', provided with a crank-pin, n', of a longitudinally-movable bed-plate, K, a plate, M', pivotally attached to said bed-plate, a pivoted table, T, and a pivoted lever, V, connected to said table, and provided with a slot, v, constructed to engage the said crank-pin n', substantially as described.

4. The combination, with a rotary grinding-disk and with a rotating shaft, N', provided with a crank-pin, m', of a longitudinally-movable bed-plate, N, a plate, M', pivotally attached to said bed-plate, a pivoted table, T, a pivoted lever, V, connected with said crank-pin, a pitman, U, joining said lever with the said table, and adjustable connections between said pitman and lever, substantially as and for the purpose set forth.

5. The combination, with a rotary grinding-disk and a sliding bed-plate, K, of arms M, pivoted to said bed-plate, a knife-supporting plate, M', pivotally connected with the free ends of said arms, means for adjusting the angle of the plate M' with reference to the arms, and means for supporting the said plate M', substantially as and for the purpose set forth.

6. The combination, with a rotary grinding-disk and a sliding bed-plate, K, of arms M, pivoted to said bed-plate, means for adjusting the pivot connecting said arms with the bed-plate laterally upon said plate, a knife-supporting plate, M', pivotally connected with the free ends of the arms, means for adjusting the angle of the plate M' with reference to the arms, and means for supporting the said plate M', substantially as and for the purpose set forth.

7. In a unitary machine for grinding cutter-knives and sharpening saws, the combination, with a stationary rotating arbor carrying two grinding-disks, and with a driving-shaft, of means for supporting and giving the necessary movements to a saw in relation to one of the grinding-disks, and a movable carrier for supporting a cutter-knife in proper position with reference to the other disk, substantially as described.

8. In a unitary machine for grinding cutter-knives and sharpening saws, the combination, with a stationary rotating arbor carrying two grinding-disks, and with a suitable driving-shaft, of means for supporting and giving the necessary movements to a saw, and means for supporting a cutter-knife and giving it a transverse vibratory motion, substantially as described.

In testimony that I claim the foregoing as my invention I affix my signature in presence of two witnesses.
